United States Patent Office

Des. 208,270
Patented Aug. 8, 1967

208,270

PAIR OF SPECTACLES OR THE LIKE

Steve Boxer, 4414 Woodman Ave.,
Sherman Oaks, Calif. 91403

Filed Aug. 10, 1966, Ser. No. 3,409

Term of patent 14 years

(Cl. D57—1)

FIG. 1.

FIG. 2.

FIG. 3.

FIG. 4.

The dominant features of my design reside in the portions shown in full lines.

I claim:

The ornamental design for a pair of spectacles or the like, substantially as shown and described.
